UNITED STATES PATENT OFFICE

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY

GENERATOR DRIVE FOR RAILROAD CARS AND THE LIKE

Application filed September 29, 1928. Serial No. 309,138.

My invention relates to improvements in generator drives and has for one object to provide a new and improved drive for generators mounted upon vehicles and adapted to be driven in response to rotation of the vehicle wheels. One application of my invention is the provision of a generator drive for railroad vehicles or cars. Another object of my invention is the provision of means, associated with such a drive, for maintaining the driving and driven pulleys in constant alignment. Another object is to provide means for permitting the removal of the vehicle wheel and axle without affecting, or necessitating the dismantling of the drive. Another object is to lengthen the life of the belts employed, and to prevent their breakage. Other objects will appear from time to time throughout the specification and claims.

My invention is illustrated more or less diagrammatically in the accompanying drawings, wherein—

Figure 1 is a plan view;
25 Figure 2 is a longitudinal section along the line 2—2 of Figure 1;

Figure 3 is a section along the line 3—3 of Figure 1;

Figure 4 is a section along the line 4—4 of Figure 2.

Like parts are indicated by like characters throughout the specification and drawings.

A generally indicates any suitable car frame and A¹ the spring suspension therefor, 35 they being not described in detail since they form no part of the present invention.

B generally indicates the car truck structure having side members B¹ B¹ and the transverse members B² B³. B⁴ B⁴ generally indicates any suitable journal boxes in which are received the ends of the axle B⁵. B⁶ B⁶ are wheels mounted upon said axle. B⁷ is a driving pulley clamped about said axle or otherwise held against rotation or longitudinal movement in relation thereto. It may for example consist of the twin segments B⁸ B⁸ secured together by the bolts B⁹. It is herein shown as cylindrical.

C is a longitudinal member or slab supported at one end upon the transverse mem-

ber B² and at the other upon the transverse member B³ for example by the downwardly depending end portions C¹ C².

Mounted upon the lower side of the slab C is the bracket member D, having the downwardly depending side flanges D¹ through which pass the pin D² to which are pivoted the bracket arms D³ supporting the bearing housing D⁴. Mounted in each end of said housing are the roller races D⁵ D⁶ provided with the rollers D⁷ in engagement with the inner roller races or sleeves D⁸ D⁹ about the reduced ends D¹¹ of the shaft D¹⁰. D¹² is a securing sleeve for one end of the housing and screw threaded into the closure member D¹⁴. The opposite end of the shaft extends through the screw threaded closure member D¹⁵ at the opposite end of the housing and receives the pulley hub D¹⁶ secured by the lock nut D¹⁷.

Pivoted to the lug E on the side of the housing D⁴ is the yoke member E¹ secured by the pin E². Screw threaded into it is the rod E³ the outer end of which is adapted to pass through the downwardly open slot E⁴ in the opposite end of the bracket D and is retained therein by the pin E⁵. E⁶ is any suitable securing pin passing through the end of the rod E³ and adapted to prevent complete withdrawal of the rod through the slot E⁴. E⁷ indicates a spiral spring compressed between the screw threaded abutment member E⁸ screw threaded upon one end of the rod E³ and the abutment member E⁹ slidable along the rod. E¹⁰ are any suitable adjustment nuts.

At the opposite end of slab C from the swinging take-up bearing is positioned the fixed bracket L¹ to which is secured the generator housing L², from which outwardly projects the motor shaft L³ carrying the driven pulley L⁴. It will be understood that the driving belt I extends about the pulleys D¹⁸ and L⁴ and is looped above the driving pulley B⁷.

The driving belt for railroad lighting generators forms one of the most difficult problems in car maintenance. It frequently happens that the cost of furnishing belts for a single car runs as high as fifty dollars per

month. The belts do not wear out so much as they break or are cut to pieces. One difficulty is that the fact that moisture gets into the ends of the belt where the belt is clamped or fastened together for assembly around the car axle. This moisture especially in winter freezes and the belt just breaks off. In summer the moisture gets into the belt and causes it to rot. Certainly 10 ninety percent and more railroad engineers will testify to this fact. My invention contemplates the provision of a short endless belt which can be water-proof throughout, thus avoiding this breakage or destruction.

15 The use and operation of my invention are as follows:

Among the prevailing problems in motor generator practice as applied to motor railroad cars, are the alignment of driving and 20 driven pulleys, the limiting of both wear and breakage of belts, and the avoidance of undue strain upon belt and generator. I provide for a positive alignment of the pulleys either by positioning the motor generator it- 25 self upon the car truck or by positioning a driven pulley upon the car truck, and providing a flexible driving connection between such pulley and the generator. In either case the relation of the pulleys is unaffected by the 30 relative movement of truck and car frame.

I employ a drive pulley fixed on the axle, a driven pulley on the car truck, constantly aligned with the drive pulley, and an idler or tension pulley, mounted on the car truck 35 and held against axial movement in relation to the drive and driven pulleys, but yieldingly positioned upon a bracket pivoted to the truck for rotation about an axis parallel with the axis of rotation of the axle. I em- 40 ploy a bracket arm D³ normally thrust by the compression spring E⁷ into tensional position, thus holding the belt I tightly against the driving pulley, the belt engaging such pulley about a substantial proportion of its 45 periphery.

The driving and the driven pulleys being close together I employ a short belt and I prefer to eliminate all difficulties caused by belt fasteners by employing a closed woven 50 or rubber belt.

It will be noted that in my device the driving connection as a unit is undisturbed when the car wheel and axle are removed. The only effect of the moving of the car wheel 55 by lowering the axle from beneath the car is to relax the tension on the belt. This not only permits easier and quicker removal of the wheel, but avoids any necessity of moving or removing parts of the drive and thus 60 avoids the risk of changes in alignment or adjustment.

I claim:

1. The combination with a railroad car truck of a generator drive frame removably 65 mounted thereon, a pair of pulleys carried

by and in fixed relation to said frame, a drive pulley on the car axle located between the pulleys of the pair, an endless belt extending around said pulleys and engaging the upper side of the driving pulley, the pair of pulleys projecting laterally from the frame and supported thereon at one side of their working faces only, an electric generator mounted on the frame, one of the pulleys being mounted on the generator shaft.

2. A generator drive for railroad cars and the like comprising a truck having a wheeled axle with a driving pulley thereon, idler pulleys mounted on the truck on either side of the driving pulley and having supports located at one side of their working faces only, a generator mounted on the truck to which one of said idler pulleys is directly connected and an endless belt traveling over the idler pulleys and engaging the driving pulley on the upper side thereof only.

3. A generator drive for railroad cars and the like comprising a truck having a wheeled axle with a driving pulley thereon, a frame removably mounted on the truck, a generator mounted on one end of the frame, a pulley mounted on the generator shaft and located at one side of the driving pulley, a pulley mounted on the frame at the other side of the generator shaft, an endless belt traveling over said pulleys and engaging the driving pulley on the upper side thereof only.

4. A generator drive for railroad cars and the like comprising a truck having a wheeled axle with a driving pulley thereon, a frame removably mounted on the truck, a generator mounted on one end of the frame, a pulley mounted on the generator shaft and located at one side of the driving pulley, a pulley mounted on the frame at the other side of the generator shaft, an endless belt traveling over said pulleys and engaging the driving pulley on the upper side thereof only, yielding means for swinging the pulley removed from the generator toward and from the generator pulley to control the tension on the belt.

5. A generator drive for railroad cars and the like comprising a truck having a wheeled axle with a driving pulley thereon, a frame removably mounted on the truck, a generator mounted on one end of the frame, a pulley mounted on the generator shaft and located at one side of the driving pulley, a pulley mounted on the frame at the other side of the generator shaft, an endless belt traveling over said pulleys and engaging the driving pulley on the upper side thereof only, the pulleys being supported on one side of their working faces only.

6. A generator drive for railroad cars and the like comprising a truck having a wheeled axle with a driving pulley thereon, a frame removably mounted on the truck, a generator mounted on one end of the frame, a pul-

- ley mounted on the generator shaft and located at one side of the driving pulley, a pulley mounted on the frame at the other side of the generator shaft, an endless belt traveling over said pulleys and engaging the driving pulley on the upper side thereof only, yielding means for swinging the pulley removed from the generator toward and from the generator pulley to control the tension on the belt, the pulleys being supported on one side of their working faces only. 70
- 5 7. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 75
- 10 an endless belt traveling over said pulleys and engaging the driving pulley on the upper side thereof only. 80
- 15 8. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 85
- 20 an endless belt traveling over said pulleys and engaging the driving pulley on the upper side thereof only. 90
- 25 9. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 95
- 30 an endless belt traveling over said pulleys and engaging the driving pulley on the upper side thereof only, yielding means for swinging the pulley removed from the generator toward and from the generator pulley to control the tension on the belt. 100
- 35 10. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 105
- 40 an endless belt traveling over said pulleys and engaging the driving pulley on the upper side thereof only, the pulleys being supported on one side of their working faces only. 110
- 45 11. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 115
- 50 an endless belt traveling over said pulleys and engaging the driving pulley on the upper side thereof only, the pulleys being supported on one side of their working faces only. 120
- 55 12. A generator drive for railroad cars and the like comprising a truck having a wheeled axle with a driving pulley thereon, a support mounted on the truck, a generator mounted on the support, a pulley mounted on the generator shaft and located at one side of the driving pulley, a pulley mounted on the support at the other side of the generator shaft, 125
- 60 an endless belt traveling over said pulleys and engaging the driving pulley on the upper side thereof only, the pulleys being supported on one side of their working faces only. 130
- 65 13. A generator drive for railroad cars and the like comprising a truck having a wheeled axle with a driving pulley thereon, 130

Signed at Chicago, county of Cook, and State of Illinois, this 10th day of September, 1928. 80
